UNITED STATES PATENT OFFICE.

CHARLES A. GOLDSMITH, OF WASHINGTON, DISTRICT OF COLUMBIA.

DESIGN FOR A SPOON.

SPECIFICATION forming part of Design No. 21,072, dated September 29, 1891.

Application filed August 18, 1891. Serial No. 403,047. Term of patent 3½ years.

To all whom it may concern:

Be it known that I, CHARLES A. GOLDSMITH, of Washington, in the District of Columbia, have invented a new and useful Improvement 5 in Designs for Spoons, of which the following is a specification.

My invention relates to a new design for spoons, as fully represented in the accompanying drawing, in which the figure shows in 10 elevation a spoon with my design thereon.

The leading feature of my design consists of a representation of the New Soldiers' Home building, the Washington Monument, and the Capitol Vista, arranged substantially as 15 shown—that is to say, the Soldiers' Home building A occupying the bowl of the spoon, the Capitol Vista B the end of its handle, and the Washington Monument C the intermediate portion of the handle, the said figures 20 being in a vertical upright position when the spoon is held with the bowl downward, as represented.

The monument is so arranged with refer-

ence to the handle of the spoon that the general contour of a portion of the latter will conform to the outline of the monument from its base to a point near its apex. 25

I propose in some cases to place upon the figure of the monument the word and letters "Washington, D. C." which are preferably, 30 but not necessarily, arranged to read downward, as shown. It is to be understood, however, that the word and letters are not deemed a feature of my design, and consequently may be omitted without affecting the same. 35

Having thus described my invention, what I claim is—

The design for a spoon, substantially as shown and described.

In testimony whereof I hereunto set my 40 hand, this 17th day of August, 1891, in the presence of two attesting witnesses.

CHARLES A. GOLDSMITH.
